UNITED STATES PATENT OFFICE.

MORTON TOULMIN, OF BALTIMORE, MARYLAND, ASSIGNOR TO THE TOULMIN ELECTRIC RAILWAY GATE COMPANY, OF SAME PLACE.

ELECTRICAL RAILWAY-GATE.

SPECIFICATION forming part of Letters Patent No. 397,880, dated February 12, 1889.

Application filed November 4, 1887. Serial No. 254,245. (No model.)

To all whom it may concern:

Be it known that I, MORTON TOULMIN, a citizen of the United States, residing at Baltimore city, in the State of Maryland, have 5 invented certain new and useful Improvements in Electrical Railway-Gates, of which the following is a specification, reference being had therein to the accompanying drawings.

10 This invention relates to improvements in railway-crossing gates.

The invention consists, essentially, of a pivoted gate-arm for closing the roadway over the tracks of a railroad and an electric motor and suitable intermediate gearing by which 15 the motor-shaft and the gate are geared or connected in such manner that the motor controls the movements of the gate-arm, it being preferred that the arm shall constantly normally tend to descend or move to a closed 20 position, and that the motor-gearing shall operate to elevate or open the gate when the motor-circuit is closed.

The invention also consists of the gate-arm, 25 the motor, and the intermediate gearing connecting the motor and gate in such manner that the gate is elevated by the rotating of the motor and intermediate electrical and mechanical devices which close the motor-circuit, maintain 30 it in a closed condition, and operate the motor until the gate-arm assumes nearly an open position, and then automatically break this circuit, whereby the motor-circuit is kept closed and the motor kept active long enough 35 to accomplish the raising of the gate-arm, notwithstanding the circuit-closer actuated by the train may remain closed momentarily only.

The invention consists, further, of certain 40 features of arrangement and construction, hereinafter more fully appearing.

In the accompanying drawings, forming a part of this specification, and on which similar letters of reference indicate the same or 45 corresponding features, Figure 1 represents a housing with the greater part of the side thereof removed, showing the mechanism of my improved gate in side elevation; Fig. 2, a plan view of said housing with the greater 50 part of the cover removed, showing said

mechanism in plan; Fig. 3, an enlarged detail view of a gate-arm, with a portion of the housing in section and elevation; Fig. 4, a detail plan view of a portion of a gate-arm and gate-shaft; Fig. 5, an enlarged detail view of 55 the primary-circuit magnet, the bell-circuit closer, and the weighted arm for throwing the worm-shaft out of gear with the worm-segment, also showing certain fixed parts in section; Fig. 6, a diagram showing certain 60 parts of the machine and the several circuits; Fig. 7, a detail plan view of parts of the apparatus; Fig. 8, a detail side view of the segment and return mechanism, and Fig. 9 a plan view thereof.

The letter A refers to a metallic housing or box of any suitable form, designed to be located near a railway-crossing and to contain the mechanism by which the gates are operated.

The letter B designates the gate-shaft, the same having bearings in the housing A, as seen more clearly in Fig. 2. Upon this shaft is loosely mounted a gate-arm, C, of skeleton form, so as to secure lightness and strength, 75 which is as nearly counterbalanced as may be. For this purpose the metallic block D is provided, a portion of which fits into the hollow heel of the gate, and is secured by a transverse bolt, E. To the longer arm of the gate 80 is pivoted a yielding stop composed of a bar, F, having a sleeve, G, at the lower end containing a spiral or other spring, and having slidingly fitted within it a foot-piece, H, whose upper end is enlarged for this purpose, and 85 whose lower end is cushioned, as by a rubber disk, I, secured thereto. The function of this yielding stop is that of preventing a serious jar to the gate-arm when it is arrested in the position shown in Fig. 3, the stop yielding as 90 it strikes the ground.

The heel of the gate is by preference provided with a spring, J, which comes against a fixed part, K, when the gate-arm assumes its elevated position, the object being to stop 95 it gradually. A rubber or other cushion, L, is also preferably provided, as shown in Fig. 3, against which the gate-arm strikes and finally rests when down.

The means by which the gate is lowered 100

exercises a rotating influence over the shaft B in the direction of the arrow shown in Fig. 1, and this motion is transmitted to the gate-arm through disks M, secured rigidly to the 5 shaft and notched at N, so as to engage with a transverse pin, O, extending through the arm. This notch allows of the rebound of the gate without affecting the shaft, and also allows the motor (hereinafter mentioned) to 10 get a fair start before the shaft engages positively with the gate-arm to elevate it.

The means referred to as acting upon the shaft B to rotate it consists, by preference, of a grooved pulley, P, secured thereto, and from 15 which a weight, Q, is suspended by a chain, (or rope,) R. The normal tendency of the shaft B to rotate is therefore in the direction of the arrow, and the normal tendency of the gate-arm is therefore that of closing or descending.

I will now describe the mechanism by which 20 this tendency is controlled, and by which the shaft B is rotated in the opposite direction to that caused by the weight Q when it is desired to elevate or open the gate. This consists of a segmental worm-wheel, S, secured 25 rigidly to said shaft B, and a worm, T, which meshes with the segment, and is thrown in and out of gear therewith, as will presently appear. The shaft of the worm is divided into 30 sections U and V, being coupled by any convenient form of universal joint, as at W. The section U at its free end is mounted in a link, X, suspended from the arm Y, and guided against lateral deflection by a jaw in the end 35 of bars Z, extending from the standards a. The arm is pivotally mounted upon a short shaft, b, having bearings in the standards a, and is extended downward and provided with a weight, c, sufficient to raise the worm T out of 40 mesh with the segment S when it (the weight) is allowed to swing down. This weight is held up by the means presently to be described in such position as to maintain engagement 45 between the worm-shaft T and segment S, whereby the shaft B is locked against rotating and the gate-arm held up. The section V of the worm-shaft has suitable bearings in 50 the housing A, and is provided with a gear-wheel, d, which meshes with a pinion, e, carried by a shaft, f, which is either a continuation 55 of the motor-shaft or is coupled therewith.

The letter g designates an electric motor of 55 any approved construction, whose function is that of rotating the shaft f, and through the intermediate devices described the worm T, worm-segment S, and the shaft B, whereby the motor is used as the motive power by 60 which to elevate the gate-arm, it being caused to descend under the influence of the weight Q, as already suggested.

The weight c is sustained against dropping 65 down and throwing the worm T out of gear with the segment S by means of a lug or hook on the armature h of the primary-circuit magnet i. This primary circuit has a circuit-closer located some distance, as at a quarter,

a half, or a full mile, in advance of the road-crossing, and mounted so as to be actuated by a passing train, and to close the circuit, energize the magnet i, and draw the lug of the armature h from beneath the weight c some time before the train reaches the crossing. This done, the weight c swings down, and, through the means already described, lifts the 70 worm T out of engagement with the segment S, and leaves the shaft B under the rotating influence of the weight Q, which immediately acts under the force of gravity to draw the gate-arm down. The segment S also moves 75 through about a quarter of a revolution with the shaft B and comes to rest upon a cushioned stop, j, secured within the housing A.

In Fig. 8 the segment is shown as approaching the limit of this quarter movement, and 80 a stud, k, projecting from a spoke of the segment S, as about to come into contact with a lever, l, pivoted upon the shaft B and supporting a rod, m, guided at n. This rod and lever constitute return mechanism, by which 85 the weight c is returned to its position upon the lug of the armature h. The support h' of the armature, being in the nature of a spring, yields to allow the weight to pass over the lug and acts to force the lug back under the 90 weight. This return of the weight c, it will be observed, automatically occurs when the gate has descended. This returns the worm T into engagement with the segment S, which 95 is now ready to elevate the gate upon the 100 closing of the motor-circuit.

To go back somewhat, I will now refer to the gong or bell circuit. A cross-piece forming a support, O, for the spring h' of the armature h also supports two metallic plates, p 105 and q, forming parts of the bell-circuit. The plate p is of a yielding nature, and is normally held out of contact with the plate q by means of a rod, r, (see Figs. 1 and 5,) suspended from the support O, and having a non-conducting termination, s, which rests upon the weight c. It will be noticed, therefore, that when the weight c swings down the rod will drop sufficiently to allow the spring-plate p to make contact with the plate q. Therefore when the magnet i is energized to allow the gate to descend the bell-circuit is at the same time closed. The circuit which energizes the magnet i, and which I term the 110 "primary circuit," is only closed for a moment, while the bell-circuit remains closed until the gate is entirely down, when the lifting of the weight c, in the manner already described, also lifts the rod r and raises the plate p away from the plate q. These actions 115 having taken place, the train is presumed to be traveling in the direction of the road-crossing. When it has passed the same, it actuates a circuit-closer located beyond the road-crossing, say, fifty or one hundred feet. This 120 circuit-closer is in what I term a "motor-closing circuit," and in which motor-closing circuit the magnet t is placed. A pivoted detent, v, stands opposite the armature u, and

is provided with a non-conducting surface, *w*, which normally engages said armature. The shaft *x* of this detent *v* carries a cam-arm, *y*, (see Figs. 1 and 2,) which acts to hold the 5 non-conducting surface *w* normally against the armature *u*, and which also draws the detent *v* over said armature when the latter has been drawn down to its magnet *t*. The armature and the detent are in the motor-circuit, 10 and when they are brought into contact in this manner the motor-circuit is thereby closed and maintained in a closed condition mechanically after the motor-closing circuit has been automatically broken by the reaction 15 of its circuit-closer, the latter being of such character as to effect this, as will presently more fully appear. Thus it will be observed that the motor-closing circuit is utilized to close the motor-circuit proper, which 20 is to remain closed long enough to give the motor time to elevate the gate-arm.

Immediately upon the armature *u* and the detent *v* becoming electrically engaged with each other the motor begins to operate, and, 25 through the mechanism already described, rotates the worm *T*. This rotation is kept up until the gate-arm is nearly elevated, when the lever *y* is engaged by a cam-block, *z*, secured to the segment *S*, and elevated sufficiently to throw the detent away from the 30 armature *u* and allow it to return to normal position. By this time the block *z* has passed from beneath the lever *y*, whereupon the non-conducting surface *w* comes again against 35 the armature *u*, and the momentum of the motor and of the gear-wheel *d* carries the gate up the remainder of the distance.

I will now refer to the preferred arrangement of the circuits, as shown in Fig. 6. In 40 this diagram, 1 designates the battery, which is composed of any required number of cells, and which, by preference, is placed in that part of the housing shown at number 2 in Fig. 2. At 3 the primary-circuit closer is located, 45 and at 4 the motor-closing-circuit circuit-closer is located. When the circuit-closer 3 is actuated, the primary circuit is made through the wires 5 6 7. This also closes the bell-circuit through the wires 8, 9, and 10 and 50 the plates *p* and *q*, already referred to. When the circuit-closer 4 is actuated, the motor-closing circuit is made through the wires 11, 12, and 13. This being done, the motor-circuit is made, in the manner above described, 55 through the wires 14 15 16, the detent *v*, and the armature *u*.

I do not confine myself to the use of any particular form of circuit-closer.

The term "intermediate gearing" in this 60 specification is used as meaning mechanism which transmits motion from the motor to the gate.

Having thus fully described my invention, what I claim as new, and desire to secure by

65 Letters Patent, is—

1. The combination, with a pivoted gate-arm having a normal tendency to descend, of

an electric motor, intermediate gearing connecting the motor with the gate-arm and controlling its descent and ascent, and an electric generator, circuits, and circuit-closers which control said gearing and motor, whereby upon closing one of said circuits the gate-arm descends and upon closing the other the motor is actuated. 75

2. The combination, with the pivoted arm and means which normally tend to close it, an electric motor, and an electric generator, of gearing between the motor-shaft and the gate-shaft which elevates the gate when the 80 motor is in operation and locks it against descent, a primary circuit, its magnet, and circuit-closer which unlock the locking parts of the gearing, a motor-starting circuit and a magnet therein, a motor-circuit of which the 85 armature of said magnet forms a part, a detent which engages said armature to maintain the motor-circuit, and cam mechanism to disengage them when the gate-arm rises. 90

3. The combination, with a gate-shaft, a pivoted detent, and intermediate cam mechanism which acts on the detent through the turning of the gate-shaft, of an electro-magnet, its armature, and an electric circuit maintained by said armature after its magnet has been 95 momentarily energized until the cam mechanism releases it from the detent. 100

4. The combination, with a gong, a generator, and a gong-circuit, an electro-magnet, its circuit, its circuit-closer, and devices between 100 said magnet and the gong-circuit which hold the latter open until said magnet is energized, of a pivoted gate and return mechanism actuated by said gate on its descent to act upon said intermediate devices and break the bell- 105 circuit. 110

5. The combination, with a pivoted gate-arm, of an electric motor, a jointed worm-shaft, one section of which is geared to the motor-shaft and the free end of the other section of which is connected with a pivoted weighted arm, an electro-magnet whose armature sustains said arm and maintains the worm in engagement with a segment on the gate-shaft until said magnet is energized, mechanism actuated by said segment to return said arm to its position after the opening of the gate, a pivoted detent in the motor-circuit, provided with a cam-lever, an electro-magnet whose armature is also in the motor-circuit, 115 which it completes when said magnet is energized, and a cam on the worm-segment to break said circuit as the gate-arm rises. 120

6. The combination, with a pivoted gate-arm and means normally tending to close it, 125 of an electric motor, intermediate gearing connecting its shaft with the gate-shaft, devices which maintain said connection, an electro-magnet which, when energized, breaks said connection, allowing the gate to descend, a 130 circuit and circuit-closer of said magnet in advance of the crossing, return mechanism actuated by the descent of the gate which re-establishes said connection, a detent, an elec-

tro-magnet whose armature, when said magnet is energized, electrically contacts with said 5 detent, cam mechanism which breaks said contact as the gate-arm rises, a circuit-closer beyond the crossing, a motor-starting circuit between said closer and the last-named magnet, and a motor-circuit composed in part of said 10 armature and detent, the circuit-closers being located near a railway-track, and an electric generator for said circuits.

7. The combination, with a pedestal and a pivoted gate-arm mounted therein, of an electric motor and intermediate gearing between

the said motor and the gate arranged to actuate the gate-arm through the motor by the 15 application of electric currents to the motor, whereby the movements of the gate are controlled by electro-motive force through mechanical instrumentalities.

In testimony whereof I affix my signature in 20 presence of two witnesses.

MORTON TOULMIN.
